BED COVER SUPPORT,
APPLICATION FILED MAY 13, 1915.

UNITED STATES PATENT OFFICE.

HELEN PAULINE JONES, (NOW BY DECREE OF DIVORCE HELEN PAULINE WASH,) OF ST. LOUIS, MISSOURI.

BED-COVER SUPPORT.

1,175,526.

Specification of Letters Patent. Patented Mar. 14, 1916.

Application filed May 13, 1915. Serial No. 27,753.

To all whom it may concern:

Be it known that I, HELEN P. JONES, a citizen of the United States, residing at the city of St. Louis, State of Missouri, have 5 invented certain new and useful Improvements in Bed-Cover Supports, of which the following is a specification.

This invention relates to supports for bed-covers and more particularly to devices for 10 supporting the bed-covers adjacent the feet of the occupant of the bed, and has for its object to provide a cheap and adjustable device of the character described that is simple and effective in operation, whereby 15 the bed-covers adjacent the feet of the occupant of the bed may be supported in an elevated position away from the occupant's feet and upturned toes when he is lying on his back.

20 Another object is to provide a device of the character described which may be adjusted to meet the requirements of the comfort of the occupant of the bed and to the thickness of the mattress.

25 Further, the present invention provides a device whereby the covers may be supported away from the feet of the occupant of the bed or may be adjusted to permit said covers to lie substantially level upon the bed.

30 The present invention, moreover, consists in the arrangement and combination of parts more particularly set forth in the specification and pointed out in the claims.

In the case, for instance, of a patient, the 35 nature of whose illness or injury requires him to lie in bed on his back with the toes of his feet turned up, it has been found that the weight of the bed-covers resting upon his toes in the ordinary arrangement of covering the patient causes great annoyance, and, in fact, when required to be endured for a great length of time, causes actual torment to the patient and becomes unendurable. By means of the present invention, 45 the bed-covers adjacent the patient's feet may be supported in an elevated position away from contact with his feet and upturned toes without uncovering the feet or the body of the patient, thus providing him with the protection and warmth desired without the annoyance and torment of supporting the bed-covers with his toes.

An advantage of the present invention consists in that the device may be operated

to support the bed-covers in an elevated position, as described, or, if desired, it may be operated to permit the bed-covers to lie upon the feet, and, in case the bed is unoccupied, the device of this invention will permit the bed-covers to be disposed upon 60 the bed in a substantially level position without removing the device, thus giving the unoccupied bed the neat, trim, and even appearance desirable in a "made up" and unoccupied bed.

65 It is, of course, understood that the device of the present invention may be used not only for the beds of the sick or injured in hospitals or elsewhere, but, also, may be used in connection with beds in homes, hotels, and the like for the comfort of well occupants.

70 In the accompanying drawings forming part of the specification, wherein like numbers of reference denote like parts wherever they occur, Figure 1 is a perspective view of the device embodying the present invention in position adapted to support the bed-covers elevated away from the feet of the occupant of a bed; Fig. 2 is an end view 75 in elevation of Fig. 1, on a reduced scale, showing the device in use in connection with the bed-covers of a bed and an occupant lying in the bed on his back; Fig. 3 is a fragmentary perspective view, on an enlarged scale, looking at an end of the device with the movable cover-supporting member in an unstable position preparatory to adjusting said member to the stable position shown in Fig. 1; Fig. 4 is a sectional 80 view, on an enlarged scale, on the line 4—4, Fig. 1, showing also in dotted lines the unstable position of the movable cover-supporting member depicted in Fig. 3; Fig. 5 is a cross sectional view of the device showing the movable cover-supporting member dropped from the dotted line position to the position adapted to support the bed-clothes in level position on an unoccupied bed; and Fig. 6 is a fragmentary sectional 85 view, on an enlarged scale, on the line 6—6, Fig. 1, showing in detail the construction of a support for rigidly holding the movable cover-supporting member in upright position.

90 100 105 Base-plate 1 may have one side attached in swinging or hinged relation to bar 2 by any suitable means, such, for instance, as by

means of the pivotal attachments 3, and each end of said bar 2 may support an upright or standard 4. Back-plate 5 may be slidably supported at opposite ends upon said standards 4, said ends of said back-plate 5 being preferably provided with hollow members 6, which members are adapted to receive said standards slidably therein, and locking means 7 may be provided borne by said hollow members, said locking means being adapted to engage said standards to lock said back-plate 5 in any desired adjusted position along the height of said standards, said standards being preferably provided with notches or the like (not shown) adapted to receive an end of said locking means, said locking means being of any suitable construction, such for instance, as the thumb-screws 7 shown in the drawings.

Top-plate 8 is borne adjacent the upper edge of back-plate 5 in hinged and slidable relation with said back-plate, so that, for the purpose of this invention, said top-plate may be swung to a substantially vertical position, shown in Fig. 3, and then dropped downwardly for a suitable distance adjacent a wall of said back-plate, as best seen in Figs. 1, 2, and in the full lines of Fig. 4, and, also, so that said top-plate may be swung from the position shown in Fig. 3 and in the dotted lines, Fig. 4, in the arc indicated by the arrows in said Fig. 4 to the position shown in Fig. 5, wherein said top-plate lies substantially horizontal to base-plate 1 and substantially at a right-angle to back-plate 5. For attaching said top-plate 8 in hinged and slidable relation to said back-plate 5, one or more looped straps 9 may be provided borne by back-plate 5, each of said straps being adapted to receive within its looped portion a corresponding pintle 10, each pintle being borne by top-plate 8 adjacent an edge of said top-plate and being adapted to extend across the mouth of an opening 11, best seen in Fig. 3, there being as many of said openings 11 as there are pintles 10, said openings being formed by cutting away portions of the material of said top-plate adjacent the pintle-bearing edge thereof, and said opening being of such size, configuration, and of such depth transversely to the length of said top-plate as will permit each pintle 10 slidably to operate in the loop of said strap 9 for moving said top-plate to and from the position shown in Fig. 3, and in the dotted lines, Fig. 4, and to and from the position shown in Figs. 1, 2, and in the full lines, Fig. 4, the loop of said strap extending upwardly above the adjacent edge of back-plate 5 sufficiently to permit top-plate 8 to be swung on its hinged attachment to and from the position shown in Fig. 3, and in the dotted lines Fig. 4, and to and from the posi-

tion shown in Fig. 5. To support top-plate 8 substantially rigidly in the position shown in Figs. 1, 2, and in the full lines in Fig. 4, one or more braces 12 (Figs. 3 and 6) may be provided borne by the wall of back-plate 5 adjacent which wall a portion of top-plate 8 lies when in the position shown in said Figs. 1, 2, 6, and in the full lines in Fig. 4, each of said braces bearing a shoulder 13 and extending therefrom beyond the upper edge of back-plate 5 to form a space or slot between said wall of said back-plate and said portion of said brace for receiving a portion of said top-plate therein, the adjacent edge of said top-plate being adapted to seat on said shoulder within said space or groove, as best seen in Fig. 6, said top-plate being thus held substantially rigidly upright in the position shown in said Figs. 1, 2, 6, and the full lines in Fig. 4, said top-plate being thus substantially locked against swinging movement when in said position.

Top-plate 8 may be supported in the position substantially horizontal to that of base-plate 1, shown in Fig. 5, by means of portions of said top-plate adjacent hollow members 6 resting on the top of said hollow members, the top of said hollow members being adapted to engage said portions of said top-plate in said position and providing stops to prevent the further movement of said top-plate toward said base-plate.

Base-plate 1, back-plate 5, and top-plate 8 may be made of any suitable material, but are preferably made of sheet metal and are of skeleton structure, as best seen in Fig. 1, said skeleton structure providing a device comparatively light in weight yet sufficiently strong for the purpose of this invention, and the free longitudinal edge of base-plate 1 may, if desired, be crimped over upon itself, as shown in the drawings, to provide a stiffening means for said plate, and, also, top-plate 8 may be similarly stiffened by having its free longitudinal edge crimped over upon itself, or, as shown in the drawings, may be stiffened by having said edge crimped over upon a bar 13, as best seen in Figs. 4 and 5. All the parts of the device embodying the present invention may be made of any suitable material, but are preferably made of metal, and of such construction as to provide sufficient strength for the purposes of this invention in a device of comparatively light weight to facilitate the handling of same.

The length of base-plate 1, back-plate 5, and top-plate 8 may be adapted to the width of the bed in connection with which the device of this invention is to be used, and the width of back-plate 5 may be adapted to the thickness of an ordinary mattress, and the width of top-plate 8 may be such that when said top-plate is in the position shown in Figs. 1, 2, and the full lines of Fig. 4, the

upper or free longitudinal edge of said top-plate will extend slightly above the upturned toes of the occupant of a bed in connection with which the device is used, as 5 best seen in Fig. 2. The width of base-plate 1 may be such as to extend for a short distance forwardly from the lower end of the mattress 14, as shown in Fig. 2.

In use, base-plate 1 is placed underneath 10 the foot end of mattress 14 in bed 15, and back-plate 5 is preferably adjusted on uprights 4 and locked in that position by means of thumb-screws 7 so that said end of said mattress may be received in the space 15 formed between base-plate 1 and top-plate 8 when said base-plate and said top-plate are in the position relative to each other as shown in Fig. 5. Top-plate 8 is then placed in the position shown in Figs. 1, 2, and the 20 full lines in Fig. 4, in which position said top-plate is held substantially rigidly as hereinabove described, while back-plate 5 is held substantially upright in the space between the foot end of the mattress and the 25 foot end of the bed by means of said foot end of said mattress on one side of said back-plate and said foot end of the bed on the other side of said back-plate, and, also, by means of portions of the bed-covers 16 30 tucked in between said back-plate and the foot of said bed, if it is desired so to dispose of said bed-covers, as illustrated in Fig. 2. The bed-covers 16 may be disposed upon the bed and over the occupant thereof, as shown 35 in Fig. 2, the portion of said covers adjacent the feet of said occupant being supported in an elevated position beyond contact with the upturned toes of the feet of said occupant, thus permitting him to lie 40 on his back without the great annoyance of supporting said covers upon his toes.

By means of sliding back-plate 5 upon standards 4, the height of the upper edge of top-plate 8 in the position shown in Figs. 45 1 and 2 may be adjusted within certain limits, and by means of thumb-screws 7, the parts may be locked in an adjusted position. If, for instance, when the bed is unoccupied, it is desired not to support the 50 portion of the covers adjacent the foot of the bed in an elevated position, top-piece 8 may be slid upwardly from the position shown in Figs. 1, 2, and the full lines of Fig. 4 to the position shown in Fig. 3 and in the 55 dotted lines of Fig. 4, and then swung in the direction of the arrows, Fig. 4, to the position shown in Fig. 5 thus permitting the covers to lie substantially directly upon the bed, and permitting the bed to present 60 the ordinary appearance, when "made up," of a bed not provided with the device of this invention.

Base-plate 1 being pivotally attached to bar 4 in swinging relation thereto, said plate 65 may be folded up against back-plate 5 and

top-plate 8 when said back-plate and said top-plate are in the position relative to each other shown in Fig. 1, or when said plates are in the position relative to each other shown in Fig. 3, and when said base-plate 70 is so folded up against said back-plate and said top-plate, the device of this invention occupies a minimum of space convenient for shipping or packing in a flat package, or a number of the devices so folded may readily 75 be packed together one upon another in a case or otherwise packed together.

Various changes in the combination and arrangement of parts may be made without departing from the nature and spirit of this 80 invention.

I claim:

1. In a device for supporting bed-covers, a bar, a pair of standards borne by said bar, a member having one longitudinal edge attached to said bar in hinged relation thereto, a second member slidably mounted on said standards, and a third member having one longitudinal edge attached to said second member in hinged relation thereto, said 85 second member being intermediate said first and third members.

2. In a device for supporting bed-covers, a bar, a pair of standards borne by said bar, a member having one longitudinal edge attached to said bar in hinged relation thereto, a second member slidably mounted on said standards, means borne by said second member adapted to lock same in adjusted 90 positions on said standards, and a third 95 member having one edge attached to said second member in hinged relation thereto, said second member being intermediate said first and third members.

3. A device for supporting bed-covers, 105 said device comprising two terminal members and a member borne intermediate said terminal member, one of said terminal members being supported in hinged relation to an adjacent edge of said intermediate member, and the other of said terminal members being supported in hinged and slidable relation to an adjacent edge of said intermediate member.

4. A device for supporting bed-covers, 115 said device comprising two terminal members, a member borne intermediate said terminal members, one of said terminal members being supported in hinged relation to an adjacent edge of said intermediate member and the other of said terminal members being supported in hinged and slidable relation to an adjacent edge of said intermediate member, the strap of the hinge attachment of said slidable member being 120 looped, said slidable member being slotted at its edge to receive said loop as said slid- 125 able member is moved to partially overlapping position in relation to said intermediate member, and means borne by said in- 130

4
termediate member adapted to limit the extent of the overlappable portion of said slide-
able member, and adapted, also, to support
said slideable member and said intermediate
member in substantially rigid relation to
each other when overlapped.

5. A device for supporting bed-covers,
said device comprising two terminal mem-
bers, a member borne intermediate said ter-
minal members, one of said terminal mem-
bers being supported in hinged relation to
one longitudinal edge of said intermediate
member, and the other of said terminal mem-
bers being supported in hinged and
15 slideable relation to the other longitudinal
edge of said intermediate member, the strap
of the hinge attachment of said slideable
member being looped, said loop extending
in a direction transverse the length of said
intermediate member, the pintle of said
hinge attachment being adapted to slide in
said loop in the direction of the width of
said intermediate member, the edge of said
slideable member being slotted to receive a
25 portion of said loop as said pintle is moved
in said loop to slide said slideable member
to partially overlapping relation to said in-
termediate member, and means borne by
said intermediate member adapted to seat
30 the edge of said slideable member, and adapt-
ed, also, to engage portions adjacent the
edge of said slideable member to hold said
slideable member and said intermediate
member in mutually rigid relation to each
35 other when overlapped.

6. A device for supporting bed-covers,
said device comprising two terminal mem-
bers, a member slidably mounted inter-
mediate said terminal members and adapted
40 to be slideably adjusted toward and away
from adjacent edge of one of said terminal
members, said edge being mounted in
hinged relation to said intermediate mem-
ber, and looped means borne by said slideable
45 member adapted to support the other of
said terminal members in hinged and slide-
able relation to said intermediate member.

7. A device for supporting bed-covers,
said device comprising a base, supporting
50 means borne by said base in hinged relation
thereto, a member slidably mounted on said
supporting means, means borne by said
member adapted to lock same in adjusted
positions on said supporting means, looped
55 means borne by said member, and a member
mounted in said looped means in hinged
and slideable relation to said slideable mem-
ber.

8. In a device for adjustably supporting
60 covers adjacent the foot of a bed, the com-
bination with a bed and a mattress and
covers therefor, of a member adapted to be
inserted beneath said mattress adjacent the
foot-end thereof, a second member borne
65 in hinged relation to said first named mem-

ber and adapted to extend upwardly adja-
cent the foot-end of said mattress, and a
third member borne by said second member
in hinged and slideable relation thereto, said
third member being adapted to be releas-
70 ably supported in upright position adja-
cent the upper edge of said second mem-
ber, the upper edge of said third member,
when upright, being adapted to support
said covers thereon, and the upper face of
75 said member being adapted to support said
covers thereon when the third member is
swung on its hinged attachment to a posi-
tion substantially at a right angle to said
second member.

9. In a device for adjustably supporting
covers adjacent the foot of a bed, the com-
bination with a bed and a mattress and
covers therefor, of a member adapted to be
inserted beneath said mattress adjacent the
80 foot-end thereof, supporting means borne
by said member in hinged relation thereto,
a second member slidably mounted on said
means adjacent the foot-end of said mat-
tress, means borne by said second member
85 adapted to lock same in adjusted positions
on said supporting means, and looped means
borne by said second member, a third mem-
ber mounted in said looped means in hinged
and slideable relation to said second member,
90 said third member being adapted to be
moved in said mounting to and from over-
lapping relation with said second member
and being adapted, also, to be swung in
said mounting in hinged relation with said
95 second member, the upper edge of said third
member being adapted to support said
covers when said member is in overlapped
position, and the upper face of said third
member being adapted to support said
100 covers when said member is swung for-
wardly to a position substantially at a right-
angle to said second member.

10. In a device for adjustably supporting
covers adjacent the foot of a bed, the com-
bination with a bed and a mattress and
covers therefor, of a member adapted to be
inserted beneath said mattress adjacent the
110 foot-end thereof, supporting means borne
by said member in hinged relation thereto,
a second member slidably mounted on said
means adjacent said foot-end, means borne
by said slideable member adapted to lock
115 same in adjusted positions on said support-
ing means, looped means borne by said
second member, a third member mounted in
said looped means in hinged and slideable
relation to said second member, said third
120 member being adapted to be moved in said
mounting to and from overlapping relation
with said second member and being adapt-
ed, also, to be swung in said mounting in
hinged relation with said second member,
125 and means borne by said second member
adapted to limit the extent of said overlap-
130

pable relation and being adapted, also, to support said third member substantially in rigid relation with said second member when overlapped, the upper edge of said 5 third member being adapted to support said cover when said member is in overlapped position and the upper face of said third member being adapted to support said cover when said member is swung forwardly to a position substantially at a right-angle to 10 said second member.

In testimony whereof I hereunto affix my signature.

HELEN PAULINE JONES.
